UNITED STATES PATENT OFFICE.

JAMES H. WHITE, OF NEW YORK, N. Y., ASSIGNOR TO THE MANHATTAN BRASS COMPANY, OF SAME PLACE.

BRACKET AND STANDARD LAMP.

SPECIFICATION forming part of Letters Patent No. 252,162, dated January 10, 1882.

Application filed July 18, 1881. (No model.)

To all whom it may concern:

Be it known that I, JAMES H. WHITE, of the city and State of New York, have invented an Improvement in Bracket and Standard Lamps, 5 of which the following is a specification.

Lamps have been made with the standard and reservoir connected by pivots, so that the lamp may be supported above the standard, or the base may be suspended by a hook against 10 a wall so that the standard is horizontal, and in some instances a spring-latch has been employed to prevent the parts turning on the pivots when the standard is either horizontal or vertical.

15 My present invention is for rendering the connection between the reservoir and the standard more firm and reliable, and for avoiding springs and catches that are liable to be broken or accidentally moved.

20 In the drawings, Figure 1 is a vertical transverse section of the lamp at the joint between the standard and the reservoir, the dotted lines showing the position of the parts when the standard is horizontal; and Fig. 2 is a view 25 partially in section of the connecting parts at right angles to Fig. 1.

The standard *a* and base *b* are of any desired size, shape, or character. So also are the reservoir *c* and burner *d*. The yoke *e*, pivot-bar 30 *i*, and nut *k* are preferably cast in one piece of metal. There is a socket or connecting thimble, *l*, between the nut *k* and the reservoir *c*, the parts being soldered or otherwise fastened together. The screw *n* passes through the nut 35 *k*, and it is provided with a thumb-wheel, *o*, and conical end *r*. The bar *i* that forms the pivot is round where it rests in the notches at the upper end of the standard *a*, and there is a hemispherical cap, *s*, to the top of the stand- 40 ard. This is notched so as to pass down around

the pivot-bearings, and it is to be soldered in place at the top end of the standard after the yoke *e*, the screw *n*, and the pivot-bar *i* have been put in place. In the surface of the cap *s* there are recesses, one at the center of the cap, 45 as at 2, and the other at one side of the cap, as at 3.

When the reservoir is to be held vertically above the standard the screw is turned down, and its conical end enters the recess 2 and 50 clamps the parts firmly in place. When the standard is turned off horizontally the parts are locked in that position by the screw *n* being turned back so that its conical end enters the recess 3.

Projecting from the pivot-bar *i* there is an arm or pin, *u*, within the standard, located as represented in Fig. 1, so that it forms a stop against the interior of the standard when it is turned into either a horizontal or a vertical 60 position. This causes the parts to stop in such a position that the recess 2 or 3 will be in line with the screw when the same is to be turned back for entering such recess and locking the parts together.

65 I claim as my invention—

1. The combination, with the standard and reservoir, of the yoke *e*, pivot-bar *i*, nut *k*, screw *n*, and cap *s*, having the recesses 2 and 3, substantially as and for the purposes set forth. 70

2. The yoke *e*, pivot-bar *i*, and arm *u*, in combination with the standard *a*, reservoir *b*, and screw *n*, substantially as set forth.

Signed by me this 13th day of July, A. D. 1881.

JAMES H. WHITE.
